CLAIM

The ornamental design for carrier for small animals or the like, as shown and described.

DESCRIPTION

FIG. 1 is a front elevational view of a carrier for small animals or the like showing my new design, the rear being a mirror image of the front shown;
FIG. 2 is a left end elevational view thereof;
FIG. 3 is a right end elevational view thereof;
FIG. 4 is a top plan view thereof; and
FIG. 5 is a perspective view taken from the top, front and right end thereof.
